CONVEYER APPARATUS

Myron A. Kendall and Chester C. Moore, Aurora,
Ill., assignors to Stephens-Adamson Mfg. Co.,
a corporation of Illinois

Application April 1, 1943; Serial No. 481,440

5 Claims. (Cl. 198—103)

Various material classifying devices such as screens and specific gravity separators function most efficiently if the material being classified is spread quite evenly across the width of the classifier. For some methods of separation, a very thin stream is essential and unless the thin stream extends the full width of the apparatus, the remainder of the apparatus is wasted.

According to the present invention, substantially uniform distribution of any loose or granular material across the width of any treating or handling apparatus can be obtained in a very simple, inexpensive and trouble-free manner which at the same time will elevate the material sufficiently to run through the treatment unit by gravity.

The preferred form of the invention comprises a circular or wheel-type elevator preferably having the partition walls forming its pockets sloping at such an angle that the last of the material being handled will slide therefrom just as the partition finishes passing over the treatment unit so that the full width of the unit will be used with substantially no excess of material. The partitions are preferably adjustable angularly to secure this result with different materials.

This application is a continuation in part of our application, Ser. No. 341,424.

Apparatus forming the embodiment of the invention at present preferred is shown in the accompanying drawings, in which

Fig. 1 is a more or less diagrammatic side elevation of one form of the invention chosen for illustration, partly broken away;

Fig. 2 is a vertical section taken approximately on the line 2—2 of Fig. 1;

Fig. 3 is a fragmentary sectional view showing the adjustable partitions in the circular elevator of Fig. 2;

Fig. 4 is a fragmentary detail showing a sectional view taken approximately on the line 4—4 of Fig. 3;

Fig. 5 is a somewhat diagrammatic side elevational view showing another modification of the invention.

This invention contemplates a combination of a special wheel-type elevator and some material handling equipment in which uniform distribution of the material laterally of the material handling equipment is important.

In Fig. 1, the material handling equipment comprises a vibrator screen 11 in which it is important to have the material spread uniformly in a reasonably thin layer across the width of

the screen panel 12. In Fig. 5, the material handling equipment is a belt conveyor 13 which may comprise a sorting or inspection table. Since the material which is hidden by an upper layer misses the inspection, it is obviously important to have the material evenly distributed in a thin layer on such a table. In our co-pending application Ser. No. 341,424, the invention has been illustrated in combination with a fine coal cleaner in which the provision of a very thin stream of coal is essential and in which the stream must be uniform across the width of the cleaner in order to use the full capacity of the cleaner.

Although an important aspect of the invention is the recognition that the combination of a material-handling apparatus requiring a thin uniform layer and a wheel-type elevator properly designed to supply this uniform layer will have exceptional efficiency, it was also necessary to make some simple although very important changes in the elevator itself. These are best explained with reference to Fig. 2.

The wheel type elevator comprises a wheel 16 supported by rollers 17 at least one of which is driven by a motor 18 to drive the wheel. The wheel is formed of side plates 19 and rim 21 so that it opens inwardly. The material 22 to be handled, possibly consisting of gravel, is dumped into the wheel 16 in any desired manner as by a belt conveyor 23. Partitions 24 are provided within the wheel 16 to form a number of pockets in which the material is raised by the wheel 16. As the partitions 24 approach the top of the wheel, the material carried thereby begins to slide off over the lips of the partitions and drop down from the wheel. The point at which this spilling will begin to occur depends on the nature of the material, particularly its angle of repose, but also on the quantity of material loaded into each pocket. The point in the cycle at which each partition 24 will begin to spill the material of a given angle of repose depends on the volumetric quantity of material which is held by the partition, or rather by the relationship between this quantity and the volume of space available for it. If a cup containing a quantity of sand were slowly tilted by hand, the angle in which the sand would spill out would depend upon how full the cup is. In the same way, the angle at which the pocket formed by a partition 24 will start to spill depends on how full the pocket is.

With wheel-type elevators of the past, a catcher has been provided to catch the material as soon as it starts to spill from a wheel-type ele-

vator and direct it to the point of use. According to the present invention, however, the construction is just the opposite. A catcher is provided in advance of the point of use as before, but instead of carrying this material to the position of use, it carries it away from the position of use usually through the chute 27 to the rising part of the elevator. The purpose of this is to prevent a piling up of excess material on the near side of the material-handling apparatus 11. Not until a partition 24 is directly above the apparatus 11 does material therefrom fall onto the apparatus. Then as the partition 24 moves across the apparatus, it is tilted further and further toward the vertical so that the material continues to be spilled therefrom with approximate uniformity. Ideally, the last of the material would be spilled just as the lip of the partition 24 passes over the far edge of the apparatus 11. This ideal can be approximated by providing the partitions 24 at the proper angle within the wheel 16. Since this angle will vary with different materials and even with the amount of moisture in a given material, the partitions 24 are preferably made adjustable as seen in Figs. 3 and 4. This adjustability may be provided in a very simple manner by resting the outer end of the partition on a plate 31 which may be welded across the wheel 16. The other end of the partition 24 is supported at each side by a bolt 32 and thumb screw 33. The bolt tightens against a slotted flange 34 formed on the partition 24. It is not necessary for the partition 24 or its flange 34 to have an extremely tight fit with the side plates 19 since there is ordinarily no movement between the two and hence the materials ordinarily handled will not leak if the fit is reasonably close. Because the slot 36 is in the flange 34 rather than in the side plate 19, there is no danger that it will cause leakage. Likewise the plate 31 prevents leakage around the outer edge of the partition 24 as well as supporting the partition.

The angles will probably not be so uniform as to always have the last of the material fall at the far edge of the apparatus 11 and in order to use the apparatus to capacity, it will probably be necessary from a practical standpoint to have the angularity of the partitions 24 such that a small amount of material is carried by the apparatus 11. For this reason, a catcher is provided beyond the apparatus 11. It is important that this catcher carry the material away from the apparatus 11 so as not to pile up an excess of the material on the far side of the apparatus 11. The catcher 38 may carry the excess material to a chute 39 which will carry it to the lower part of the wheel 16.

With some material, it may be found that greater uniformity of distribution across the apparatus 11 is provided if a substantial amount of the material is carried beyond the apparatus 11 so that so long as the apparatus is being spilled on the material, its rate of spill will be controlled by the angle of repose of the material itself rather than its angle of slide on the metallic partition 24. However, by slightly roughening the surface of the partition 24, it is believed that the carrying of any substantial excess of material beyond the apparatus 11 will be unnecessary.

Of course, it is not necessary that all of the material which is treated drop truly vertically from the partitions 24 to the apparatus 11. It should drop directly in the sense that it is not gathered-in or deflected transversely of the apparatus 11 but there is no harm in its being gathered

in longitudinally of the apparatus 11 as by the plates 41. This might be described as dropping without transverse deflection.

The feeding apparatus may desirably include a loading tray 42 for sifting the material in a thin stream onto the screening panel 12 or other treating member. The loading ledge 43 will tend to maintain a small reservoir of material in the loading tray 42 and thus spread the stream from each of the partitions 24 just enough to provide the desired uniformity in the loading of the screen 12 or other treating member.

The loading tray 42 is rigidly mounted with the screen panel 12 so that both are vibrated together by an eccentric shaft 46 which is driven by the motor 18 or an independent motor. If a single motor is used, the shaft 47 for driving the vibrating mechanism will usually be a relatively high speed shaft while the shaft 48 for driving the elevator will be a relatively low speed shaft. The elevator, of course, must not be driven at a speed high enough to throw the material outwardly therein by centrifugal force and keep it from spilling out downwardly near the top of the wheel.

The fairly high speeds of reciprocation of the apparatus 11 will cause the material which is fed fairly uniformly across the loading pan 42 to spill over the ledge 43 with very satisfactory uniformity.

In view of the fact that the quantity of material being fed determines the position at which any given material being fed will spill over the lips of partitions 24, it is desirable to feed the material to the elevator 16 at a very uniform rate. For this purpose, the material may be fed to belt 23 by any sort of uniform flow feeder indicated diagrammatically at 51. In the form thus illustrated, the rate of flow may be adjusted by a vertically adjustable plate 52. The feeder 51 has been illustrated as a gravity feed bin but, of course, it could be any other type of feeder. The material may be fed thereto by a chute 53 or in any other manner.

If the material is being fed uniformly by the belt 23 to the wheel 16, the return to this wheel of any material which does not fall on the treating apparatus 11 might result in a cumulative excess which would ultimately exceed the capacity of the wheel 16 and which in any event would be lifted over and over with a consequent waste of power. Accordingly, it may be desirable under some circumstances to return the excess material (by which is meant all that does not reach the unit 11) to the constant feeder 51. To accomplish this, gates 54 are provided which may be swung by hand to cause the excess material to drop down through chutes 56 instead of chutes 27 and 39. The chutes 56 lead to constant feeder 51. Of course, many installations will be built with either the chutes 56 or the chutes 27 and 39 but not both, depending largely on whether or not the constant feeding feature will always be used.

It is not essential to use a constant feeder. Whatever material is fed will be spread across the unit 11 at a uniform rate. If there is enough material fed to be spread at this rate across the entire width of the unit 11, the entire width will be used. If occasionally more than this quantity is fed, the excess will be returned to the wheel. This excess can be maintained until the volume of feed is deficient when the excess will supply the deficiency so long as the excess lasts.

The structure in Fig. 5 may be substantially

identical with that in Fig. 2 except for the treating unit, or in this instance a handling unit. In this instance, the material spilled from the partitions 24 may drop directly onto a belt 13 which may comprise an inspection or sorting table 58. If preferred, the deflector 59 may be provided so that all the materials dropped from the partitions 24 will either hit this deflector or the plates 41. This will tend to spread the individual streams from the partitions 24 so that a uniformity comparable to that produced by loading tray 42 will be provided. Of course, a reciprocating loading tray such as 42 could be provided between the wheel 16 and the belt 13 if desired, but for most purposes, the uniformity resulting without this vibrating tray will be sufficient.

Fig. 5 has shown a slightly different arrangement of return chutes. In this instance, the chutes 27 and 39 of Fig. 2 are replaced by a chute 61 which extends from below the junction of chutes 56 to a convenient point within the wheel 16. With this arrangement, a single gate 62 is all that is required to cause the material to be returned optionally to the feeder 51 or directly to the wheel 16.

It should perhaps be made clear that the use of conveyor 23 is not essential. In some instances, it may even be desirable to dump the material directly into the wheel 16 from shovels or wheelbarrows and in any event, the apparatus will be particularly useful where it is necessary to elevate the material as well as to distribute it uniformly across the handling apparatus 11 or 13.

From the foregoing, it is seen that a combined material handling apparatus and elevator and feeder therefor has been provided in which the handling apparatus functions at its best with a thin layer of material spread uniformly thereacross, this uniform feeding being accomplished by the wheel type elevator which is provided with pocket-forming partitions at such an angle that the spilling of the material continues all the way across the handling apparatus. Piling up at either side of the handling apparatus is avoided by virtue of the fact that any material which is spilled from the elevator laterally to either side of the handling apparatus is not directed to the handling apparatus but is directed away from it and returned either to the wheel or the feeding apparatus controlling the supply to the wheel. In this way, uniform loading of the material handling apparatus is accomplished.

It will be apparent that in the practice of this invention, the angularity of the partitions 24 is very important. The one essential requirement in this regard in order to use the full width of the handling apparatus with maximum efficiency is that the angularity be such that the spilling of the material continues far enough across the treating apparatus that some of the material will land at the far edge of the working area, or close enough thereto so that it will spread there by the natural flow of the material in the apparatus with sufficient ease to provide the desired uniformity in depth of material all across the working area. In the case of a screen, the working area is of course the effective width of the screen panel. It will be observed from Fig. 2 that the material is projected forwardly as it is discharged. This follows both from the movement of the wheel and from the flow of the material along its angle of repose. For this reason, it is not necessary that the partitions discharge material directly over the far edge of the work area for

material discharged at that point would land beyond the work area.

The angularity necessary to cause the last of the material carried by a partition to spill onto the far edge of the work material depends upon the nature of the material and on the nature of the surface of the partition. Most materials which it is expected to handle with this apparatus have an angle of repose of around 40°.

As seen in Fig. 2, the lip of partition 24a from which material is being discharged almost at the edge of the work area, is about 12 or 13 degrees beyond the high point of the wheel. It, therefore, has an angularity of about 12 or 13 degrees steeper than the angularity of the partition with respect to the wheel. Angularity with respect to the wheel means the angularity with respect to a line tangent to the wheel at the lip of the partition. The slope of partition 24a as shown is 40° so that if its surface were roughened so that the material would slide therealong as if sliding on itself, the illustrated angularity would be approximately correct for a material having an angle of repose of 40° and for apparatus having other parts in the proportion shown. However, the angularity of the partition 24a with respect to the wheel is only in the neighborhood of 28°. The features of adjustability shown in Fig. 3 should be such as to permit adjustment of angularity to at least as low as 20° (unless a larger angle is known to be small enough for a particular material to be treated) and with some materials or with an angularly wider work area, it might be desirable for the angle to be still lower.

With respect to the point at which the spilling begins, the angularity of the partitions is not important and hence their angularity should depend entirely upon the desired terminal point of the spilling. The commencing point of spilling will be determined by the loading of the elevator and the nature of the material.

The end walls 66 and 67 at the sides of the work area have been shown slightly sloping to correspond approximately to the trajectory of the material at this point. If the wall 66 were vertical, its shadow-area with reference to the trajectory might cause a zone of sparse feeding beside it. If the wall 67 were vertical, the rebound of the material from it might cause excessive feeding in the zone beside it. In this instance, incidentally, it might be noted that if under certain conditions, the feeding of the material is found to be ragged near the wall 67 with a tendency toward sparseness in this zone, it might be desirable to have the wall 67 vertical or even slope it slightly outwardly to compensate for this raggedness and provide greater uniformity of feed. On the other hand it may be found one or both of the end walls of the loading tray 12 should be sloped for the reasons described in connection with walls 66 and 67.

We claim:

1. Material handling apparatus including supply means, a handling unit substantially thereabove requiring material to be fed thereto in a layer and for maximum capacity requiring the feeding to be uniform across the width thereof, and means for elevating material to be classified from the supply means and feeding it uniformly along substantially the full width of said unit comprising a wheel-type elevator having a rim, sides extending inwardly therefrom not over one-fourth the radius of the rim and pocket-forming partitions therein subdividing over half of the

cross-sectional area between the sides and which at the upper part of the elevator pass transversely of and above the unit and which are disposed at such an angle that some material will be retained on each partition, as it passes across the unit, long enough to fall, without deflection laterally of the unit, substantially at the far edge of the work area of the unit, and chute means at both sides of the unit for carrying all material which is spilled from the partitions laterally to either side of the unit back to the handling apparatus.

2. Material handling apparatus including supply means, a handling unit substantially thereabove requiring material to be fed thereto in a layer and for maximum capacity requiring the feeding to be uniform across the width thereof, and means for elevating material to be classified from the supply means and feeding it uniformly along substantially the full width of said unit comprising a wheel-type elevator having a rim, sides extending inwardly therefrom not over one-fourth the radius of the rim and pocket-forming partitions therein subdividing over half of the cross-sectional area between the sides and which at the upper part of the elevator pass transversely of and above the unit and which are disposed at such an angle that some material will be retained on each partition, as it passes across the unit, long enough to fall, without deflection laterally of the unit, substantially at the far edge of the work area of the unit, and chute means at both sides of the unit for carrying all material which is spilled from the partitions laterally to either side of the unit back to the handling apparatus, said partitions being adjustable as to angularity to spill the last of the material approximately onto the far edge of the work area of the unit.

3. Material handling apparatus including supply means, a handling unit substantially thereabove requiring material to be fed thereto in a layer and for maximum capacity requiring the feeding to be uniform across the width thereof, and means for elevating material to be classified from the supply means and feeding it uniformly along substantially the full width of said unit comprising a wheel-type elevator having a rim, sides extending inwardly therefrom not over one-fourth the radius of the rim and pocket-forming partitions therein subdividing over half of the cross-sectional area between the sides and which at the upper part of the elevator pass transversely of and above the unit and which are disposed at such an angle that some material will be retained on each partition, as it passes across the unit, long enough to fall, without deflection laterally of the unit, substantially at the far edge of the work area of the unit, chute means at both

sides of the unit for carrying all material which is spilled from the partitions laterally to either side of the unit back to the handling apparatus, and means for loading the elevator uniformly with a load of such volume that it will begin to spill from the partition at substantially the right time to fall onto the near edge of the work area without deflection laterally of the unit.

4. Material handling apparatus including supply means, a handling unit substantially thereabove requiring material to be fed thereto in a layer and for maximum capacity requiring the feeding to be uniform across the width thereof, and means for elevating material to be classified from the supply means and feeding it uniformly along substantially the full width of said unit comprising a wheel-type elevator having a rim, sides extending inwardly therefrom not over one-fourth the radius of the rim and pocket-forming partitions therein subdividing over half of the cross-sectional area between the sides and which at the upper part of the elevator pass transversely of and above the unit and which are disposed at such an angle that some material will be retained on each partition, as it passes across the unit, long enough to fall, without deflection laterally of the unit, substantially at the far edge of the work area of the unit, said partitions being adjustable as to angularity to spill the last of the material approximately onto the far edge of the work area of the unit.

5. Material handling apparatus including supply means, a handling unit substantially thereabove requiring material to be fed thereto in a layer and for maximum capacity requiring the feeding to be uniform across the width thereof, and means for elevating material to be classified from the supply means and feeding it uniformly along substantially the full width of said unit comprising a wheel-type elevator having a rim, sides extending inwardly therefrom not over one-fourth the radius of the rim and pocket-forming partitions therein subdividing over half of the cross-sectional area between the sides and which at the upper part of the elevator pass transversely of and above the unit and which are disposed at such an angle that the last of the material will be spilled approximately at the right position to fall, without deflection laterally of the unit, substantially at the far edge of the work area of the unit, and means for loading the elevator uniformly with a load of such volume that it will begin to spill from the partition at substantially the right time to fall onto the near edge of the work area without deflection laterally of the unit.
